CLAIM

The ornamental design for an insect trap, as shown and described.

DESCRIPTION

FIG. 1 is a front view of an insect trap showing my new design;

FIG. 2 is a rear view thereof;

FIG. 3 is a right side view thereof;

FIG. 4 is a left side view thereof;

FIG. 5 is a bottom view thereof;

FIG. 6 is a top view thereof;

FIG. 7 is a perspective view thereof; and,

FIG. 8 is another perspective view thereof.

The lightened areas within the circular edge in FIGS. 1 and 7, as well as the broken lines within the circular edge, depict portions of the insect trap that form no part of the claimed design.

1 Claim, 8 Drawing Sheets
